ROADWAY FORMATION UNIT

Ernest H. Geyer, Chicago, Ill., assignor of one-half to Henry A. Taubensee, Chicago, Ill.

Application December 2, 1938, Serial No. 243,493

7 Claims. (Cl. 94—18)

The present invention relates to devices for use in the formation of a roadway consisting of adjoining slabs of concrete.

In the formation of a roadway of this character or type, it is customary in some instances to fill the spaces between the slabs with plastic filler material after formation of the slabs and to employ between the adjoining slabs dowel rod joints which act as load transfer means and have the ends thereof slidably mounted in the opposed portions of the slabs so that the slabs are free to expand or contract in response to temperature changes. It is further customary before pouring the concrete for the slabs to position the dowel rods in laterally spaced relation and at the desired height above the roadbed and then to place on the roadbed and across the central portions of the rods a space-forming board having in the lower portion thereof downwardly facing V-shaped notches for accommodating or receiving the central portions of the dowel rods. After proper placement or positioning of the board on the roadbed the notches are filled with any suitable plastic material such as clay or putty in order to prevent the concrete during pouring thereof in connection with slab formation from flowing from one side of the board to the other. As soon as the concrete sets and roadway forming slabs are thus formed at the sides of the board, the board is removed and thereafter the notch filling material is removed from beneath the central portions of the dowel rods and the space between the slabs is filled with the plastic filler material. In practice it has been found that the work incident to filling the notches in the board after placement of the board on the roadbed and across the central portions of the dowel rods and the work of removing the notch filling or closing material from beneath the dowel rods after removal of the board from between the slabs, requires a considerable amount of time and materially delays completion of the roadway.

One object of the invention is to provide a device which is adapted for use in connection with a joint forming dowel rod and serves with a group of like devices to eliminate the laborious, time-consuming work hereinbefore referred to.

Another object of the invention is to provide a device which is capable of being applied to a space forming board of the aforementioned character before placement of the board on the roadway and is adapted effectively and efficiently to close the downwardly facing notch for the dowel rod with which it is associated and in addition is adapted to remain in assembled relation with

its dowel rod after removal of the board from the roadway.

A further object of the invention is to provide a notch closing device of the last mentioned character which serves temporarily to hold the dowel rod with which it is associated in connected relation with the board so that the rod and board may be assembled or connected together prior to placement over the roadbed and pouring of the concrete at either side of the board.

A still further object of the invention is to provide a device of the type under consideration which is simple in design and may be manufactured at a low and reasonable cost.

15 Other objects of the invention and the various advantages and characteristics of the present device will be apparent from a consideration of the following detailed description.

The invention consists in the several novel 20 features which are hereinafter set forth and are more particularly defined by claims at the conclusion hereof.

In the drawings which accompany and form a 25 part of this specification or disclosure and in which like numerals of reference denote corresponding parts throughout the several views:

Figure 1 is a perspective view showing a device embodying one form of the invention in operative relation with respect to a dowel rod 30 and before attachment to a notched space forming board;

Figure 2 is a perspective view showing the device of Figure 1 together with its dowel rod after attachment to the board and prior to pouring of 35 the slab forming concrete at the sides of the board;

Figure 3 is a sectional view on a smaller scale showing the device of Figures 1 and 2 and the dowel rod assembly and board after pouring of 40 the concrete;

Figure 4 is a similar sectional view showing the device and dowel rod assembly after removal of the space forming board and filling of the space between the slabs with the seal forming plastic 45 filler material;

Figure 5 is a perspective view of the device of Figures 1 to 4, inclusive;

Figure 6 is a sectional view showing a device 50 embodying a second or modified form of the invention in assembled relation with a dowel rod and a space forming filler board;

Figure 7 is a small scale perspective view of the device of Figure 6;

Figure 8 is a sectional view showing a device 55 embodying a third form of the invention in as-

sembled or associated relation with a dowel rod assembly and a notched space forming board; and

Figure 9 is a perspective of one part of the device of Figure 8.

The device which is shown in Figures 1 to 5, inclusive, constitutes one form of the invention. It is adapted for use with a dowel rod assembly 10, and a filler board 11 in the formation of a roadway comprising a pair of adjoining concrete slabs S on a roadbed B. As shown in Figure 4, the slabs S are spaced slightly apart and have a filling 12 of plastic filler material therebetween. The dowel rod assembly 10 operates to transmit load from one slab to the other and permits the slabs to expand and contract as the result of changes in temperature or climatic conditions. It is adapted to be assembled and placed on the roadbed prior to pouring of the concrete in connection with formation of the slabs S and comprises a dowel rod 13, a sleeve 14, and a pair of stress reducers 15. The board 11 is adapted, as hereinafter described, to be placed on the roadbed B and across the central portion of the dowel rod assembly 10 and serves to separate the slabs S during pouring of the concrete therefor and to form a space s between the slabs. It is greased before it is placed in position on the roadbed B in order to prevent the concrete from becoming bonded thereto, and is preferably formed of wood. Instead of being formed of wood the board may be formed of metal or any other suitable material or the board may be covered with sheet metal. After formation of the slabs, the board 11 is removed and the space s is filled with the filling 12, as well understood in the art. The dowel rod 13 of the dowel rod assembly 10 constitutes a load transfer member and fits slidably within and is of less length than the sleeve 14. It is formed of solid steel or other suitable material and is arranged so that its ends project into the slabs, as shown in Figures 3 and 4, and the central portion thereof projects or extends across the space s. The sleeve 14 has its ends plugged or otherwise closed and is formed of such metal or material that the ends thereof become bonded to the slabs s after formation of the latter. The central portion of the sleeve is weakened by means of longitudinally extending slots 16 so that it ruptures in connection with initial contraction of the slabs and thus permits the sleeve ends to move with the slabs and to slide on the ends of the dowel rod 13. The stress reducers 15 are tubular and fit on the end portions of the sleeve 14, as shown in sheet 1 of the drawings. They are formed of semi-cylindrical sections and embody laterally extending wings 17. In addition to the wings, the stress reducers embody at the outer ends thereof U-shaped legs 18. The latter are designed to rest on the roadbed B and serve to support the dowel rod assembly 10 in place and against tilting during pouring of the concrete for the slabs S. The side pieces of the legs are welded or otherwise fixedly secured to the outer ends of the wings 17. The board 11 for separating or spacing apart the slabs S during pouring of the concrete therefor is adapted to rest on the roadbed B and is preferably of slightly greater height than the slabs. It embodies in the lower portions thereof a downwardly facing V-shaped notch 19. The central portions of the dowel rod 13 and the sleeve 14 of the dowel rod assembly 10

fit within the upper end of this notch when the board and assembly are in their operative position on the roadbed prior to pouring of the concrete for the slabs S. The device which constitutes the first form of the invention and is shown in Figures 1 to 5, inclusive, serves temporarily to hold the dowel rod assembly 10 in connected relation with the filler board 11 and also to close the notch 19 against the flow of concrete therethrough. It is preferably formed of thin sheet metal and comprises a pair of side pieces 20 and 21 and a bottom connecting piece 22. The side pieces 20 and 21 are designed to fit against the sides of the board 11 and have circular axially aligned holes 23 therein for the central portion of the sleeve 14 of the dowel rod assembly. They are of sufficient width effectively to close the notch 19 and are adapted to be pressed into snug fitting relation with the sides of the board 11 by the wing equipped stress reducers 17. The bottom connecting piece 22 extends between and is formed integrally with the lower margins of the side pieces 20 and 21. It is adapted to underlie and close the bottom of the notch 19 in the board 11 and serves to prevent concrete from flowing under the side pieces and into the notch. The side piece 21 is of greater height than the side piece 20 and is adapted to have the upper end thereof bent over the top of the board 11, as shown in Figures 2 and 3, in order temporarily to hold the device and dowel rod assembly in connected relation with the board. In forming the roadway forming slabs S the sleeve 14 with the dowel 13 therein is inserted through the holes 23 in the side pieces 20 and 21 and is then adjusted until it is centrally positioned with respect to the device. Thereafter the wing equipped stress reducers 17 are slid onto the ends of the sleeve 14 and into abutment with said side pieces. At the conclusion of this step the dowel rod assembly 10 is applied to the board 11 by bringing the central portion of the sleeve into alignment with the bottom of the notch 19 and then raising the assembly until the central portion of the sleeve engages the top of the notch and the bottom connecting piece 22 of the device bears against the bottom of the board. After so positioning or assembling the dowel rod assembly, the upper end of the side piece 21 is bent over the top of the board by striking it with a hammer or other suitable tool. After bending the upper end of the side piece 21 into place the stress reducers 17 are urged inwards as far as possible in order to bring the side pieces 20 and 21 into snug engagement with the sides of the board. When the device consisting of the side pieces 20 and 21 and the bottom connecting piece 22 is in place, the dowel rod assembly 10 is in attached relation with the board and the sides and bottom of the notch 13 are effectively closed. After connecting or attaching the assembly to the board by bending the upper end of the piece 21 over the top of the board, the board with the assembly is placed on the roadbed B, as shown in Figure 3. Thereafter the slabs S are formed by pouring concrete on either side of the board. As soon as the concrete sets or hardens the upper inwardly bent end of the side piece 21 is swung upwards, as shown in dotted lines in Figure 2, and the board 11 is removed from between the slabs by prying or sliding it upwards. After removal of the board the upper projecting end of the side piece 21

of the device is either cut away by a sheet metal cutter or saw, or it is bent inwardly beneath the top faces of the slabs S. After this operation the space s between the two slabs S is filled or poured full of plastic filler material to form the filling 12. The device which is shown in Figures 1 to 5 may be manufactured at a low and reasonable cost because of its simplicity of design and effectively and efficiently fulfills its intended purpose. It has a two-fold purpose in that it serves as a seal or closure for the notch 19 in the board and at the same time constitutes an attaching medium whereby the dowel rod assembly 10 may be attached to the board 11 prior to placement of the board on the roadway bed B. Whereas only a single device has been shown and described in sheet 1 of the drawings, it is to be understood that a plurality or group of devices together with dowel rod assemblies are used in connection with the formation of the roadway forming slabs S.

The device which is shown in Figures 6 and 7 constitutes a second or modified form of the invention. It is adapted for use with a dowel rod assembly 10^a and a filler board 11^a in the formation of a slab formed roadway (not shown). The dowel rod assembly 10^a is the same in design and construction as the assembly 10 of Figures 1 to 4, inclusive, with the exception that it embodies no U-shaped legs for supporting it against tilting during pouring of the concrete for the roadway forming slabs. It serves as a load transfer means or medium, the same as the assembly 10 and consists of a dowel rod 13^a, a sleeve 14^a, and a pair of stress reducers 15^a. The rod, sleeve and stress reducers are the same in design and serve the same purpose as the rod 13, the sleeve 14 and the stress reducers 15 constituting the dowel rod assembly 10. The board 11^a is adapted to be placed on the roadbed and across the central portion of the dowel rod assembly 10^a and embodies in the lower portion thereof a downwardly facing V-shaped notch 19^a for accommodating such portion. The device which constitutes the second form of the invention serves temporarily to hold the dowel rod assembly 10^a in connected relation with the board 11^a and in addition operates to close the notch 19^a against the flow of concrete therethrough and to hold the dowel rod assembly 10^a against tilting during pouring of the concrete. It is formed of sheet metal and consists of a pair of U-shaped parts 24 and 25. The part 24 comprises a pair of vertically extending side pieces 26 and 27 and a bottom connecting piece 28. The piece 28 is formed integrally with and extends between the lower ends of the side pieces 26 and 27 and is adapted to rest on the roadbed. The side pieces 26 and 27 have notches 29 in the upper portions thereof for receiving one end of the sleeve 14^a of the dowel rod assembly 10^a. The side piece 27 is adapted to fit against one side of the board 11^a, as shown in Figure 6, and serves to close one side of the notch 19^a. The side piece 26 is disposed adjacent the outer end of the adjacent stress reducer 15^a and coacts with the side piece 27 to hold the assembly 10 against tilting. The U-shaped part 25 is adapted for placement against the other side of the filler board 11^a and consists of a pair of vertically extending side pieces 30 and 31 and a bottom road bed engaging bottom piece 32. The side pieces 30 and 31 have notches 33 in the upper ends thereof for receiving the adjacent end of the sleeve 14^a of the dowel rod assembly 10^a. The side piece 31 is

adapted to fit against the board 11^a, as shown in Figure 6, and serves in conjunction with the side piece 27 of the U-shaped part 24 to close the sides of the downwardly facing V-shaped notch 19^a. The side piece 30 coacts with the side piece 26 of the part 24 to hold the assembly 10^a against tilting during pouring of the concrete. In order to close the bottom of the notch against the flow of concrete, the part 24 is provided with an auxiliary bottom piece 34 and the part 25 is provided with an auxiliary bottom piece 35. The piece 24 fits against and is riveted to the bottom piece 28 of the part 24 and projects inwardly under the inner portion of the bottom piece 32 of the part 25. The auxiliary bottom piece 35 is riveted to the bottom piece 32 of the part 25 and projects under the auxiliary bottom piece 34, as shown in Figures 6 and 7. The auxiliary bottom pieces 34 and 35 form a sliding lap joint for closing the bottom of the notch 19^a in the filler board 11^a. By having the pieces 34 and 35 in sliding engagement with one another, the lap joint is expandable and contractible and hence adapts itself for use in connection with filler boards which vary in thickness. In order temporarily to hold the parts 24 and 25 in connected relation with the filler board 11^a the side pieces 27 and 31 are provided at their upper ends with opposed inwardly extending beads 36. These beads, as shown in Figure 6 of the drawings, are adapted when the parts 24 and 25 are in associated relation with the board 11^a to fit within longitudinally extending grooves 37 in the sides of the board. The grooves are positioned above the notch 19^a in the lower portion of the board 11^a. In assembling the device of Figures 6 and 7 with respect to the dowel rod assembly 10^a and the board 11^a, the part 24 is first shifted upwards in order to bring the adjacent end of the sleeve 14^a within the notches 29. When the part 24 is in its proper position, the upper ends of the side pieces 26 and 27 straddle or bear against the ends of the adjacent stress reducer 15^a. After application of the part 24 to the dowel rod assembly, the part 25 is shifted upwards in order to bring the opposite or other end of the sleeve 14^a into the notches 33 in the upper ends of the side pieces 30 and 31. At the conclusion of this step or operation, the assembly together with the device is shifted upwards in order to bring the central portion of the sleeve 14^a into the upper end of the notch 19^a in the board 11^a. During this shifting operation the beads 36 at the upper ends of the side pieces 27 and 31 snap into the grooves 37 in the sides of the board and thus hold the device of Figures 6 and 7 together with the dowel rod assembly 10^a in temporary connected relation. After attachment of the device to the board, the board, assembly and device are placed on the roadbed and concrete is poured at either side of the board. As soon as the concrete hardens the board 11^a is removed. Thereafter the board formed space is filled with plastic material, as well understood in the art. The notches 29 and 33 preferably have restricted entrances, as shown in Figure 7, in order that the parts 24 and 25, when applied to the sleeve, tend to remain in place. The device of Figures 6 and 7 is simple in design and hence is capable of being manufactured at a low and reasonable cost. It is usable in connection with a thick or thin filler board and is characterized by the fact that it serves in addition to closing the notch 19^a against the flow of concrete therethrough and holding the dowel rod assembly 10^a in temporary connected

relation with the filler board 11^a to support the assembly against tilting during pouring of the concrete at the sides of the board.

The device which is shown in Figures 8 and 9 constitutes a third embodiment of the invention. It is adapted for use with a dowel rod assembly 10^b and a filler board 11^b in connection with the formation of a slab formed concrete roadway (not shown). The assembly 10^b is the same in construction and design as the assembly 10 of the assembly of Figures 1 to 4, and comprises a dowel rod 13^b, a centrally weakened dowel rod encasing sleeve 14^b, and a pair of stress reducers 15^b. The stress reducers fit snugly and slidably on the central portion of the sleeve 14^b and are provided with outwardly extending wings 17^a and U-shaped legs 18^b. The legs are adapted to rest on the roadbed and serve to hold the assembly against tilting during pouring of the concrete. The filler board 11^b serves the same purpose as the filler boards 11 and 11^a and embodies in the lower portion thereof a downwardly facing V-shaped notch 19^b for accommodating the central portion of the sleeve 14^b. The device of Figures 8 and 9 serves temporarily to hold the assembly 10^b in connected relation with the filler board 11^b and in addition operates to close the notch 19^b against the entry or flow of concrete. It is preferably formed of sheet metal and comprises a pair of complementary parts 38. The latter consist of side pieces 39 and bottom pieces 40. The side pieces are adapted to fit against the sides of the board 11^b, as shown in Figure 8, and have holes 39^a in the upper ends thereof for the central portion of the sleeve 14^b. The bottom pieces 40 are formed integrally with and project outwardly from the bottom margin of the side pieces 39 and are adapted to rest on the roadbed. The outer ends of the bottom pieces 40 have transversely extending downwardly facing grooves 41 for the central or intermediate portions of the U-shaped legs 18^b. The parts 38 embody wires 42 at the upper ends thereof and these wires, as shown in Figure 8, are adapted to be twisted together at the upper ends thereof in order to form a saddle or yoke around the upper portion of the board 11^b. The side pieces 39, when in their operative position, are pressed into firm or snug contact with the sides of the board by the stress reducers 15^b. The device of Figures 8 and 9 is assembled by first passing the sleeve 15^b through the holes 40 in the side pieces 39. Thereafter the stress reducers 15^b are slid onto the ends of the sleeve. After the last operation the dowel rod assembly 10^b together with the parts 38 are raised or otherwise moved in order to bring the central portion of the sleeve 14^b into the upper end of the notch 19^b in the lower portion of the filler board 11^b. After such manipulation, the wires 42 are bent inwards over the top of the board 11^b and then twisted. After assembly of the device the board 11^b is placed over the roadbed and concrete is poured at either side thereof to form the roadway forming slabs. After hardening of the concrete, the wires 42 are cut and the filler body 11^b is raised from between the slabs. Thereafter, the board formed space is filled with plastic material. During pouring of the concrete at the sides of the board 11^b the side piece 39 of the parts 38 close the sides of the notch 19^a against the flow of concrete into the notch. By employing the transversely extending grooves 31 in the bottom pieces 40 so

that such pieces are in hooked relation with the U-shaped legs 18^b of the dowel rod assembly 10^a, the lower portions of the side pieces are held in firm contact with the sides of the filler board 11^b. The device of Figures 8 and 9 is simple in design and hence may be manufactured at a low and reasonable cost.

The invention is not to be understood as restricted to the details set forth, since these may be modified within the scope of the appended claims, without departing from the spirit and scope of the invention.

Having thus described the invention, what I claim as new and desire to secure by Letters Patent is:

1. A unit adapted for use in roadway formation and comprising in combination a filler board having a notch in the lower portion thereof and adapted to be placed on a roadbed and to have concrete poured at the sides thereof for roadway slab forming purposes and further adapted upon hardening of the concrete to be removed from between the slabs, a load transfer member having the central portion thereof extending through the notch and its ends adapted for embedment in the slabs, a pair of side pieces fitting against the sides of the board and across the notch for preventing entry of the concrete into the notch prior to hardening of the concrete and removal of the board, and bead and groove connections between the side pieces and the sides of the board for temporarily securing said pieces in connected relation with the board.

2. A unit adapted for use in roadway formation and comprising in combination a filler board having a downwardly facing notch in the lower portion thereof and adapted to be placed on a roadbed and to have concrete poured at the sides thereof for roadway slab forming purposes and further adapted upon hardening of the concrete to be removed from between the slabs, a load transfer member having the central portion thereof extending through the upper portion of the notch and its ends adapted for embedment in the slabs, a pair of side pieces mounted on said central portion of the load transfer member and fitting against the sides of the board and across the notch for preventing entry of the concrete into the notch prior to hardening of the concrete and removal of the board, and a pair of slidably engaging lap joint forming bottom pieces at the lower ends of the side pieces for closing the bottom of the notch when the board is in its operative position.

3. A unit adapted for use in roadway formation and comprising in combination a filler board having a notch in the lower portion thereof and adapted to be placed on a roadbed and to have concrete poured at the sides thereof for roadway slab formation purposes and further adapted upon hardening of the concrete to be removed from between the slabs, a load transfer member having the central portion thereof extending through the notch and its end adapted for embedment in the slabs, stress-reducers slidably mounted on portions of the ends of the member and provided with downwardly extending roadbed engaging legs for holding the member against tilting during pouring of the concrete, a pair of side pieces mounted on the central portion of said member and fitting against the sides of the board and across the notch for preventing entry of the concrete into the notch prior to hardening of the concrete and removal of the

board, and means extending between the lower ends of the side pieces and the legs for holding said lower ends of the side pieces in firm abutment with the sides of the board.

4. A unit adapted for use in roadway formation and comprising in combination a filler board having a downwardly facing notch therein and adapted to be placed on a roadbed and to have concrete poured at the sides thereof for roadway slab formation purposes and further adapted upon hardening of the concrete to be removed from between the slabs, a load transfer member having one portion thereof extending through the notch and other portions adapted for embedment in the slabs, and a pair of side pieces for preventing entry of concrete into the notch prior to hardening of the concrete and removal of the board and having notches in the upper ends thereof for said one portion of the load transfer member.

5. A unit adapted for use in roadway formation and comprising in combination a filler board having a downwardly facing notch in the lower portion thereof and adapted to be placed on a roadbed and to have concrete poured at the sides thereof for roadway slab forming purposes and further adapted upon hardening of the concrete to be removed from between the slabs, a load transfer member having the central portion thereof extending through the upper portion of the notch and its end portions adapted for embedment in the slabs, and a pair of side pieces for preventing entry of the concrete into the notch prior to hardening of the concrete and removal of the board fitting against the sides of the board and having in the upper ends thereof notches with restricted entrances for said central portion of the load transfer member.

6. A unit adapted for use in roadway formation and comprising in combination a filler board having a downwardly facing notch in the lower portion thereof and further adapted upon hardening of the concrete to be removed from between the slabs, a load transfer member having the central portion thereof extending through the upper portion of the notch and its ends adapted for embedment in the slabs, a pair of tubular stress reducers extending around portions of the ends of the member and disposed at opposite sides of the board, and a pair of U-shaped devices positioned at the sides of the filler board and beneath said member and consisting of upstanding inner side pieces held by

the inner ends of the stress reducers against the sides of the board and across the notch and serving to prevent entry of the concrete into the notch prior to hardening of the concrete and removal of the board, flat roadbed engaging bottom pieces connected to and extending outwardly from the lower ends of the inner side pieces and outer side pieces extending upwardly from the outer portions of the bottom pieces and in substantially parallel relation with the inner side pieces and having the upper ends thereof abutting against the outer ends of the stress reducers and extending around the adjacent parts of the member so that they serve to hold said member against tilting relatively to the roadbed during pouring of the concrete.

7. A unit adapted for use in roadway formation and comprising in combination a filler board having a downwardly facing notch in the lower portion thereof and adapted to be placed on a roadbed and to have concrete poured at the sides thereof for roadway slab forming purposes and further adapted upon hardening of the concrete to be removed from between the slabs, a load transfer member having the central portion thereof extending through the upper portion of the notch and its ends adapted for embedment in the slabs, and a pair of U-shaped devices positioned at the sides of the filler board and beneath the load transfer member and consisting of upstanding inner side pieces fitting against the sides of the board and across the notch and serving to prevent entry of the concrete into the notch prior to hardening of the concrete and removal of the board, flat roadbed engaging bottom pieces connected to and extending outwardly from the lower ends of the inner side pieces, outer side pieces connected to and extending upwardly from the outer portions of the bottom pieces and positioned in substantially opposed and parallel relation with the inner side pieces, and slidably engaging lap-joint forming auxiliary bottom pieces connected to and extending inwardly from the first mentioned bottom pieces and serving to close the bottom of the notch when the board is in its operative position, certain of said side pieces of the devices have means at the upper ends thereof whereby they are attached to the adjacent parts of the load transfer member and serve to hold said member against tilting relatively to the roadbed during pouring of the concrete.

ERNEST H. GEYER.
